UNITED STATES PATENT OFFICE.

EUGENE GEORGE CAMELINAT, OF BIRMINGHAM, ENGLAND.

MEANS FOR SUPPORTING LAMPS.

1,328,125.

Specification of Letters Patent. Patented Jan. 13, 1920.

Application filed March 17, 1919. Serial No. 283,266.

To all whom it may concern:

Be it known that I, EUGENE GEORGE CAMELINAT, citizen of France, residing at Birmingham, England, have invented certain new and useful Improvements in Means for Supporting Lamps, of which the following is a specification.

This invention relates to lamp brackets for use on motor cars and other vehicles, motor-cycles and the like.

The object of the present invention is to enable a standardized form of bracket to be readily applied to any type of vehicle or machine, while also admitting of adjustment of the lamp in both a horizontal and a vertical plane.

According to the invention the bracket is hinged or jointed (so as to be adjustable in a vertical plane) to a pillar or post which is adapted to fit into a socket carried by the vehicle or the like and to be adjustably fixed therein, with the lamp in any desired position in the horizontal plane, by means of a clip or other suitable fastening device.

Figure 1 of the accompanying drawings is a side elevation showing the improved means for carrying an electric motor-car lamp.

Fig. 2 is a vertical section showing the upper portion of the bracket adjusted relatively to the lower portion.

Fig. 3 represents a vertical transverse section on line x^1 , Fig. 1.

Fig. 4 is a cross-section on line x^1 , Fig. 1. Fig. 5 illustrates a section taken through the joint on line x^2 , Fig. 1.

Fig. 6 shows a horizontal section through the socket and stem, on line x^3 , Fig. 1.

Fig. 7 represents the various component parts of the fitting separately, in front and side elevation and partly in section.

Fig. 8 shows a modification of the means for locking the knuckle joint.

Referring to Figs. 1 to 7, the bracket consists of a vertical stem 1, attached at its upper end to the lamp body 2 in the manner hereinafter described, and provided at its lower end with a lug or tongue 3 which engages between the vertical jaws or cheeks 5 of a fork 4 carried at the summit of a pillar 5 adapted to enter a socket 6 attached to a suitable part of the vehicle. A screw-pin or bolt 7 fitted with a clamping nut 8 and spring washer 9 is passed transversely through the fork and lug so as to form a

knuckle joint, permitting of the adjustment of the lamp in a vertical plane, the lamp being adapted to be fixed in any adjusted position by tightening up the clamping nut. To insure the joint being more securely locked, however, two washers, 10, 10, serrated on both faces, are placed in recesses 11, 11, in opposite faces of the knuckle tongue member 3 so as to engage with the plain inner faces of the jaws of the fork 6 member. These jaws are also extended rearwardly into lugs 12 which are pierced with internally toothed holes to receive a transverse cotter pin 13 provided with longitudinal teeth adapted to engage with teeth or serrations formed around the circular periphery of the inner or tongue member 3 of the knuckle, thus constituting a positive lock. The cotter 13 is fitted with a nut 14 at one end.

The pillar or post 5 has a stop shoulder 15 at its upper end, and below this shoulder it is provided with longitudinal serrations. The socket 6 consists of a split tube provided at its upper end with lugs 16, on opposite sides of the slit, fitted with a bolt 17 and nut 18 with spring washer 19. The mouth of the socket is of slightly smaller internal diameter than the lower part, and is formed around its interior with vertical serrations 20 corresponding to, and adapted to be engaged by, the serrations of the pillar 5. By tightening up the bolt 17 the serrated part of the socket can be contracted around the pillar so as to hold the latter in position and positively prevent rotation thereof. By raising or lowering the pillar the height of the lamp can be adjusted, and by partially rotating it in the socket (the bolt being slackened) the angle in the horizontal plane at 95 which the light is projected can likewise be adjusted.

The upper part 21 of the bracket stem is externally screw-threaded and is of D-section, or other non-circular section, being 100 adapted to be passed through a correspondingly shaped hole in a socket member 22 attached to the underside of the lamp. The socket member 22 has a reduced portion which is externally screw-threaded and is 105 adapted to be engaged by a union-nut 23 swivelly attached to the stem by means of an internal flange of the nut 23 engaging beneath a collar 24 secured to the stem. The union-nut 23 can be fixed by means of a 110

Having fully described my invention, what I desire to claim and secure by Letters Patent is:—

55

1. A lamp bracket for vehicles and the like comprising a stem for attaching to the lamp, a pillar, a knuckle joint comprising fork and tongue members between the lower end of the stem and the upper end of the pillar, the opposite plain faces of the tongue member having recesses, friction washers having both faces serrated located in said recesses in the tongue member and engaging the plain faces of the fork member, means for locking the joint in different angular positions, a split socket receiving the pillar, and means for contracting the socket around the pillar to fix the latter in different angular positions within the 60 socket.

65

2. A lamp bracket for vehicles and the like comprising a stem adapted to be attached to the lamp, a pillar, a knuckle joint between the lower end of the stem and the upper end of the pillar comprising fork and tongue members, a clamping nut on the joint pin for tightening the joint, a locking pin passed through the fork member of the joint so as to engage the periphery of the tongue member, a socket receiving the pillar, and means for fixing the pillar in different angular positions within the 75 socket.

80

3. A lamp bracket for vehicles and the like comprising a stem adapted to be attached to the lamp, a pillar, a knuckle joint comprising fork and tongue members between the lower end of the stem and the upper end of the pillar, a clamping nut on the joint pin for tightening the joint, a locking pin passed through the fork member of the joint and having longitudinal teeth engaging teeth on the periphery of the tongue member, a socket receiving the 90 pillar and means for fixing the pillar in different angular positions within the socket.

85

In testimony whereof I have hereunto set my hand in presence of two subscribing witnesses.

EUGENE GEORGE CAMELINAT.

H. O. PRATT.

lock-nut 25 mounted upon a screw-threaded part of the stem so as to bear upon the lower face of the union-nut. The upper end of the stem protrudes into the interior of the lamp body and is fitted with a nut 26 adapted to be screwed down on to a flat bearing washer 27 surrounding the stem and secured to the interior of said body.

In order to lead the flexible electric conductors to the lamp, the pillar 5 and the stem 1 are drilled axially at 28, 29, respectively, and upon opposite sides of the knuckle joint are drilled with lateral holes 30, 31, leading into the axial holes, the conductor being passed, as shown, up the pillar 5, through the lateral hole 30 near the top so as to bridge the joint, and through the lateral hole 31 at the bottom of the stem 1 and thus up the axial hole 29 of the said 20 stem to the lamp.

In a modification, instead of the knuckle joint being positively locked by a toothed cotter, a plain cotter may be employed adapted to engage either a plain periphery 25 of the knuckle member, or suitable facets on the latter.

It is to be understood that the knuckle joint may be locked in its adjusted position by any convenient means. For instance, as 30 shown in Fig. 8, the pin 7 may have a serrated, square or other non-circular sectioned middle part 32 engaging a corresponding serrated or non-circular hole in the tongue member 3 of the joint and provided at one 35 end with a head 33 having its inner face serrated to engage serrations on the outside face of the fork 4, as at 34, while at the other end a serrated washer 35, feathered to the pin 7 by the key 36, can be taken into engagement with serrations 37 on the jaw of the fork 4 by means of the nut 8. Serrated washers 10, 10, are fitted in recesses of the tongue 3 as in the previous form.

The support or upper part of the bracket 45 may be of any suitable type. It may, for instance, be of the usual forked type engaging sockets on the sides of the lamp, the stem of the fork being knuckle jointed to the socket pillar.

50 The invention is equally applicable to motor-cycles, in which case the socket may be formed by the handle-bar stem.
